Dec. 508

Walter W. Wright of Boston, Mass.
Letters Patent No. 568 Dated Oct. 5th 1852

The schedule referred to in these Letters Patent and making part of the same

To all persons to whom these presents shall come:

Be it known that Walter

Bryant, of Boston, in the County of Suffolk, & State of Massachusetts have produced a new and original design for the supporting parts of a table and hereby declare that the said new design is fully described and represented in the following specification and accompanying drawings to which reference is herein after made.

The figures of the accompanying plates of drawings represent my new design. In Plate 1. Fig. 1. is an elevation of the side frame or edge of the table and Fig. 2 a longitudinal section of the same. In Plate 2 fig. 3. is a plan or top view of the leg of the table & Fig. 4 is a longitudinal vertical section of the same taken in the plane of the line A.B. fig. 3. - In Plate 3 Fig. 5. is a plan of the cross brace of the table, fig. 6. is a vertical section of the same taken in the plane of the line C.D and fig. 7. is a transverse vertical section taken in the plane of the line E.F. Fig. 5. -

The side piece a a of the table is composed of the central leaf scroll b b fig. 1 pl. 1. and the scrolls c c &c.

The leg Fig. 3. pl. 2. has in it the large leaf d d, grapes e e, scroll f f and raised buds g g, &c.

The cross brace h h h h has turned on it the grape vine and leaves i i, which meet in the centre with the grapes k k.

Having thus described my new design I shall state my claim as follows: -

That I claim as my production and desire to have secured to me by Letters Patent is the new design consisting of the scroll vine & leaf work, herein above described & represented in the drawings, for the side piece, leg and cross brace of a table.
